UNITED STATES PATENT OFFICE

SVEND BRAMSEN AND WILLIAM HERSLER, OF CHICAGO, ILLINOIS

SPRAYING APPLIANCE

Refiled for abandoned application Serial No. 257,391, filed February 27, 1928. This application filed January 20, 1930. Serial No. 422,240.

This application is a continuation and re-filing of our application No. 257,391, filed February 27th, 1928 on a spraying appliance.

Our invention relates to spraying appliances and in some of its general objects aims to provide a better balancing of manually held spraying appliances, a novel and unitary arrangement of the air control valves, novel means for sealing the valve body to the air ducts, a detachable assembly permitting the ready removal of the air valve assembly, a novel lever arrangement for actuating the main air valve, and a novel barrel construction.

In some of its more particular aspects, our invention includes the following objects:

(1) To provide air controlling means disposed so as to counterbalance the head of a spray gun, whereby the entire appliance will be approximately balanced in the user's hand.

(2) To provide means suitable for separately controlling the supply of air to a plurality of ducts and to have these air control means detachable as a unit from a body member of the appliance.

(3) To provide air controlling means in which the valve body is retained in operative position of the assembling of the tubular handle of the spray appliance.

(4) To provide simple and readily releasable means for securing such a valve body in sealing relation to the corresponding air ducts within the handle of the appliance.

(5) To provide air control means in which a manually operable member controls the entire admitted air while separately adjustable members proportion the admitted air to different air ducts.

(6). To provide an air-proportioning arrangement for this purpose in which one of the proportioning members is mounted on another one, and in which the entire valve mechanism is detachable as a unit from the body of the appliance.

(7) To provide a handle construction designed for preventing contact of the user's hand with the air control means.

(8) To provide a lever of high leverage for opening the main air control valve.

(9) To provide a valve arrangement affording an unusually long bearing for the stem of the main air control valve. 55

(10) To provide a valve-operating lever constructed so as to clear the air tubes within a relatively thin handle.

(11) To provide novel and easily assembled means for pivoting the main valve-operating lever upon the handle. 60

(12) To provide a spray-gun barrel construction which will combine ease of manufacture with unusual lightness.

Still further and also more detailed objects will appear from the following specification and from the accompanying drawings, in which

Fig. 1 is a central, vertical and longitudinal section through a spray gun embodying our invention, with the main air control valve in its closure position.

taken through the handle along the line 12—12 of Fig. 1.

Fig. 13 is an enlarged central and longitudinal section through the barrel of the spray gun before other parts are attached to the same.

Figs. 14 and 15 are enlarged sections, taken respectively along the lines 14—14 and 15—15 of Fig. 13.

Fig. 16 is a section taken along the line 16—16 of Fig. 13.

In the illustrated embodiment of our invention, our appliance is a so-called spray gun having as its body member a barrel 1 secured to a hollow handle 2. This handle consists mainly of two counterpart halves hookingly engaging opposite sides of a rear portion of the barrel, for which purpose each handle half has at its upper end an inwardly directed flange 3 socketed in a corresponding groove in the barrel, as shown in Fig. 3.

Extending through the barrel or body member 1 and generally longitudinal of the same are three passages; namely, a liquid passage 4 to which paint or other liquid is supplied through a liquid inlet 5 and which passage terminates at the forward end of the gun in a liquid discharge port 6; a main air passage 7 leading to an annular air port 8 concentric with the said port 6 and through which a sheath of air is projected around the discharged stream of liquid; and a supplemental air passage 9 connected by an annular air chamber 10 and grooves 11 with forwardly converging air ports 12 through which air jets are projected for flattening the spray from the gun.

The air passages 7 and 9 both have inlets facing the bore of the hollow handle and respectively open to the upper ends of two air supply tubes 13 and 14, which tubes extend downwardly within the handle. Mounted within the lower end of the handle is a substantial T-shaped valve body (shown separately in Fig. 6) comprising an approximately horizontal tubular body portion 15, an upwardly extending tubular shank 16 within which the stem 17 of the main air valve is slidable, and a downwardly directed inlet 18. This inlet 18 houses both the head 19 on the valve stem 17 and a spring 20 continuously pressing the head toward a seat 21, and the spring abuts at its lower end against an annular shoulder within a detachable nipple 22.

This nipple is threaded at its lower end for attaching the usual hose through which compressed air is supplied to the spray gun, and the nipple has its upper portion radially enlarged into a polygonal head 23 fitting a corresponding shape of the lower ends of the handle parts 2, as shown in Fig. 10. These handle halves are also curved toward each other as shown in Fig. 9, so as to under-hang the horizontal tubular portion 15 of the

valve body, and the interfitting of these handle parts with the nipple end 23 prevents the nipple from unscrewing when a hose is being detached from it.

The lower ends of the handle parts also have recesses for respectively receiving the head 24 and the polygonal body 25 of a nut carrying a screw 26 which presses the valve body upwards so as to clamp the air tubes 13 and 14 tightly between the valve body and the gun barrel 1, and the handle recess portions adjacent to the polygonal body 25 fit this to hold it against rotation. The air tubes 13 and 14 are connected respectively by ports 28 and 27 to the bore 29 of the horizontal tubular portion of the valve body, which bore is connected at its rear end to an air chamber 32 above the seat for the valve head 19.

Threaded into the horizontal valve body bore 29 is a tubular valve member 30 which presents a head 31 outside the handle and which has its rear end slidable past the inlet to the port 28 so as to control the connection between that port and the air chamber 32. Threaded into the tubular valve member 30 is an auxiliary control member 33 which can be rotated by a head 34 disposed in front of the head 31. This auxiliary control member 33 has a bore 35 opening at its rear end to the bore 29 through which air is supplied to the tube 13, and this bore 35 opens through a lateral port 36 into an annular chamber 37 between a shoulder on this auxiliary control member 33 and a shoulder in the bore 35 of the control member 30.

The annular chamber 37 is connected by a radial port 38 in the valve member 30 to an annular enlargement 39 in the bore 29 of the valve body, from which annular chamber the port 27 leads to the air tube 14, thereby connecting the air tube 14 with the bore of the control member 33 regardless of the rotational position of the latter member whenever that member is sufficiently retracted to open the radial port 39.

To move the head 19 of the main air valve away from its closure seat against the pressure of the spring 20, we interpose a connecting lever between the stem of that valve and the usually trigger-shaped actuating lever 40, which actuating lever or trigger is connected in any customary manner to the needle valve 41 controlling the discharge of liquid through the liquid outlet 6. Since this trigger 40 is preferably in front of the handle while the main valve stem 17 is behind the air tubes 13 and 14, the connecting lever must clear these tubes. To allow for this in a compact and light handle construction, we form the lever so that it will pass between at least one handle side and both air tubes, and we preferably have portions of the lever extending at opposite sides of the tubes to afford spaced bearings for the lever. For this

purpose, the drawings show a bell-crank lever formed from a single piece of resilient sheet metal to form a frontal bight 42 in the end of the lever arms 43, which arms project 5 forwardly through an opening in the handle to dispose this bight for engaging the trigger-shaped actuating lever 40.

The main portions of the connecting lever extend downwardly within the handle at opposite sides of both of the air tubes to present spaced bearings 41 fitting over journaling means associated with the two handle halves, which handle halves also are clamped together by two vertically spaced screws 45 15 and 46.

For this journaling we preferably provide each handle half 2 with an inwardly projecting stem 50 on which one of the lever bearings 41 journals, and an adjacent boss 51 20 against which the corresponding bearing end of the lever is pressed by the resiliency of lever. With the journaling stems 50 disposed in axial alinement and extending between the two air tubes (as shown in Fig. 12) and the lever formed so that its resiliency tends to spread its bearing portions farther apart than the bosses 51, the assembling of the handle halves with the lever between them effects the desired pivotal connection of the 25 lever to the handle, and the resiliency of the metal of the lever keeps its bearing portions spread apart to prevent rattling and to keep the shanks of the longitudinally V-sectioned 30 level freely spaced from the air tubes 13 and 14. Extending beyond the bearing 41 from at least one of the arms 43 of the connecting 35 lever and transversely of the valve stem 17, the lever has another arm 47 presenting its free end above and in engagement with the 40 free upper end of that valve stem.

With our spray gun thus constructed, a rearward movement of the actuating lever (trigger) 40 rocks the bell-crank lever and depresses the main air valve stem 17 so as to 45 open that valve and permit air to enter both the air chamber 32 and the bore 35 of the auxiliary control member. This air is then proportioned between the air pipes 13 and 14 according to the positions of the main control 50 member 30 with respect to the valve body, and also according to the position of the auxiliary control member 33 with respect to the said main control member, while the total admission of air to the tubes 13 and 14 depends on the totals of the areas of the ports 55 28 and 38 which are open.

For example, if the auxiliary control member is unscrewed from its position of Fig. 1 to afford an opened area of the port 38 corresponding to the area left open in the port 60 28 by the inner end of the main control member 30, the air will be equally divided between the tubes 13 and 14; whereas a relative change in these opened port areas will effect 65 a correspondingly changed proportion in the

air supply to these tubes, and through the two tubes respectively to the annular air sheath outlet 8 and the auxiliary air jet ports 12. Likewise, by screwing the auxiliary control member 33 inwardly to close the port 27 70 entirely, the supply of air to the auxiliary air ports 12 can be shut off completely when the spray gun is to be used for projecting an unflattened spray.

With such a spray gun employed for a flat spray, the auxiliary valve member can be initially screwed back to shut off the supply for the spray-flattening supplemental air jets, while the main control member 30 is adjusted to admit air in suitable quantity and pressure for the air sheath around the projected liquid, in proportion to the pressure at which liquid is fed to the gun and also to the intended spread of the spray. Then the auxiliary control member 33 is unscrewed sufficiently for causing air through the auxiliary air outlets 12 to flatten the spray, and if necessary the position of the main control member 30 can be readjusted. By proceeding in some such manner, the user can readily adjust our valve arrangement with a high degree of accuracy for securing both the desired total projection of air and the effective proportioning of the quantity and velocity of the air which issues respectively from the annular outlet 8 and from the auxiliary air outlets 12.

When this adjustment has once been made in proportion to the pressure at which the liquid is supplied and to the characteristics of the liquid, the adjustment need not be altered and no skill is then required in using the spray gun.

The mere retraction of the trigger lever until it is stopped (as for example by engagement with the handle after the manner shown in Fig. 4) insures a more than adequate supply of air at the rear ends of the two control members, since the air inlet chamber 32 is preferably much larger in effective section than the joint areas of the ports 27 and 28. The once established positioning of the two control members then definitely determines the amount of air fed to each of the air tubes 13 and 14, and the adjusted proportioning is not affected by the opening or closing of the main air valve. To prevent the hand of the user from contacting with the heads 31 and 34 of the two control valves during the use of the spray gun, we preferably provide each handle half with a projection 52 overhanging these valve heads.

By having the main valve stem extending vertically within the handle, we can provide a much longer bearing for it than has been possible with the customary constructions in which this valve stem was disposed substantially horizontally in the handle, since the width of the handle needs to be quite limited to make it fit a human hand. By merely 130

- clamping the air tubes 13 and 14 (at least at one end) against one of the parts connected by these tubes, we greatly facilitate the cleaning of the tubes if this should be required.
- 5 And by employing a single-piece valve body we expedite its manufacture. So also, by mounting one control member within the other, we provide an unusually compact double control arrangement.
- 10 Moreover, by mounting the valve arrangement in the lower end of the handle we cause the valve assembly to counterbalance the weight of the head of the spray gun, so that the complete appliance is approximately balanced about its neck portion and hence fatigues the user less during its manipulation than the usual type of spray gun in which the valves are mounted close in to the barrel or in the barrel itself.
- 15 20 So also, by employing a main air valve disposed behind the air tubes in the handle and near the lower end of the handle, we can make the forward arm 43 of the valve-operating lever much longer than the lever arm 47 which engages the stem of the valve, thereby securing such a leverage as to reduce the digital pressure required on the trigger in proportion to a given strength of the valve spring 20.
- 25 30 With the valve-actuating lever made of resilient metal and initially formed as shown in Fig. 8, and with alined journaling stems 50 formed on the two handle halves (which desirably are die-cast), I facilitate the mounting of the lever in the handle, as no screw needs to be fished through the journaling bearings of the lever. Moreover, the spaced bearings for this lever prevent any undesirable rocking and also permit the main portions of the lever to be freely spaced both from the air tubes and from the bore of the handle.
- 35 40 To facilitate the machining of the barrel of our spray gun and to make this barrel lighter than it would be if all of the needed passages were cast in it, we preferably employ the construction shown on an enlarged scale in Figs. 13, 14 and 15. In this construction, the gun barrel casting (which desirably is die-cast of 45 aluminum) has the forward portions of the passages 7 and 9 cored in the forward end of the barrel and leading from the bore of the main (medial) barrel portion, and also has the inlet portions 7B and 9B of the said passages leading to this bore from the neck 7 of the barrel casting. This medial main bore portion initially consists of a simple tube of generally circular transverse section, provided with inwardly directed fins 52 extending longitudinally from opposite sides of the said tube 1, as shown in Fig. 14, the opposed ends of the fins 52 being concaved toward each other.
- 50 55 Then we insert into this barrel from its rear end a guide tube 54 which serves as the

mounting for the usual means employed to guide the stem of the needle valve 41, and solder the ends of the tube respectively to the passage-bored forward portion 55 and the rearward neck portion 56 of the barrel casting. We likewise preferably provide a relatively large and downwardly directed liquid inlet bore 57 in the head portion 55 of the gun barrel casting and solder a liner tube 58 into this bore 57, which liner tube has an annular groove 59 disposed for connecting the parts of the passage 9 which are forward and rearward of the said bore 57. This liner tube arrangement permits our forming the passages 57 and 9 by cores which intersect and support each other, while the use of the inserted guide tube 54 permits both this tube and the surrounding barrel portion 1 to be of quite thin metal, so that we secure an unusually light barrel construction in which the fins 52 cooperate with the guide tube 54 to afford passage portions 7 and 9 of arcuate transverse section respectively above and below the said fins, which passage portions can be quite narrow radially of the barrel.

60 65 We also core out the barrel casting so as to leave an annular passage 60 connecting the medial part of the air passage 7 with the inlet portion 7B of this passage, and for this purpose leave the rear ends of the fins 52 connected by a lower arcuate casting portion in the form of a web 61, which has its upper end soldered to the guide tube 54 and which forms a partition between the annular passage 60 and the inlet passage portion 9B.

70 75 However, while we have illustrated and described our invention in an embodiment including numerous desirable details of construction and arrangement, we do not wish to be limited to these. Changes may obviously be made without departing either from the spirit of our invention or from the appended claims, and we also do not wish to be limited to the use of the various novel features of our invention in conjunction with one another.

80 85 We claim as our invention:

1. A spray appliance including a body member provided at its forward end with a spray head and having at its rear end a downwardly directed neck, a hollow handle comprising a pair of handle halves interlocked at their upper ends with the said neck, a valve body mounted in and having its major portion jointly housed by the handle halves, and releasable means for drawing the handle halves toward each other to clamp them against the neck and to cause the lower handle portions to retain the valve body therein.
2. A spray appliance construction as per claim 1 in which the neck and the valve body each have two socket formations respectively entered by end portions of the two tubes.
3. A spray appliance construction as per claim 1, in which the said releasable means

comprise screws connecting the handle halves, in combination with lever journaling means carried by and extending transversely of the handle, and a lever pivoted on the journaling 5 means.

4. A spray appliance including a body member provided at its forward end with a spray head and having at its rear end a downwardly directed neck, the body member 10 having two separate air passages leading from the lower end of the neck to the spray head; a hollow handle secured at its upper end to the neck, a plural valve assembly mounted in the lower end of the handle, and 15 two air tubes housed by the handle and connecting the valve assembly respectively with the said air passages.

5. A spray appliance as per claim 4, in combination with means interposed between 20 the handle and the valve assembly for pressing the latter toward the said neck to clamp the air tubes therebetween.

6. A spray appliance as per claim 4, in which the valve assembly includes a valve 25 controlling the supply of air for both air tubes, and means for opening the said valve, the valve opening means including a lever straddling both air tubes.

7. A spray appliance as per claim 4, in 30 which the valve assembly includes a valve controlling the total supply of air for both air tubes, the said valve having a stem extending upwardly within the handle, and a lever pivoted in the handle and having one 35 arm disposed for moving the valve stem, the lever having another arm projecting through a frontal portion of the handle.

8. A spray appliance as per claim 4, in which the valve assembly includes a main 40 air valve having an upwardly directed valve stem behind the two air tubes, and a two control means respectively controlling the admission of air to the two tubes; in combination with a bell-crank lever pivoted within the 45 handle and having one lever arm disposed for moving the said valve stem, the other arm of the lever projecting forwardly through the handle.

9. In a spraying appliance, a hollow 50 handle, a pair of air supply tubes mounted in the handle, and two valve members respectively controlling the admission of air to the two tubes, each valve member having a digitally movable portion disposed outside 55 the handle, the handle having a projection adjacent to the said digitally movable portions to prevent contacting of the latter with the hand holding the handle.

10. In a spray appliance having a hollow 60 handle and an air control valve mounted in the handle, and having an air supply pipe extending longitudinally within the handle, a valve-operating lever formed of metal doubled upon itself to form two shanks connected by a bight projecting forwardly

through the lever and having the two shanks disposed within the handle at opposite sides of the pipe, and pivoting means within the handle and extending through both shanks of the lever, one shank of the lever being continued beyond the pivoting means and disposed for actuating the air control valve. 70

11. A spray appliance construction as per claim 10, in combination with an operating lever outside the handle and disposed for engaging the bight of the said valve actuating lever. 75

12. In a spray appliance, a hollow handle comprising two handle halves, a valve mounted in the handle, and a longitudinally V-sectioned valve-operating lever formed of a metal strip doubled upon itself to form two shanks and having aligned journaling perforations in its shanks spaced from its bight, each handle half having a journaling stem 80 extending inwardly of the handle through one of the journaling perforations. 85

13. A handle and lever construction for a spray appliance as per claim 12, in which the lever is made of resilient metal and 90 formed so that its resiliency tends to spread the perforated lever shank portions further apart than the outer ends of the journaling stems. 95

14. In a spray gun, a barrel, a hollow handle extending secured at its upper end to the barrel, air control means mounted on the lower end of the handle and including a valvestem extending upwardly within the handle, two air tubes disposed within the handle forward of the said stem and connecting the air control means with the barrel, the said tubes being 100 forwardly spaced from each other, and means upon the handle and extending between the tubes for pivotally connecting the lever to the 105 handle. 100

15. In a spray gun, a barrel, a hollow handle extending downwardly from the barrel and having a frontal aperture, an actuating lever extending in front of the aperture, air control means including a valve stem extending within the handle, and a valve-actuating lever of substantially V-shaped longitudinal section; the lever including two shanks extending within and pivotally connected to the handle and a bight connecting the two shanks and projecting through the said aperture for engagement by the actuating lever. 110 115

16. In a spray gun, a hollow handle having a frontal aperture, an air valve carried by the handle and having a valve stem extending upwardly within the handle, and a valve-actuating lever comprising two spaced shanks extending through the said aperture and connected outside the handle by a bight, the main portions of both shanks being disposed within and journaled to the handle, and an arm on one of the shanks for engaging the valve stem. 120 125

17. In a spray gun, a barrel having a tubu- 130

lar medial portion and having longitudinal fins projecting inwardly from opposite sides of the said medial portion, and a tube disposed within the barrel and sealed to both fins to afford two spaced longitudinal air passages.

18. In a spray gun, a barrel having a tubular medial portion and having longitudinal fins projecting inwardly from opposite sides of the said medial portion, and a tube disposed within the barrel and sealed to both fins to afford two spaced longitudinal air passages, the opposed inner edges of the two fins having counterpart arcuate transverse sections, and a tube corresponding in outside diameter to the said arcuate sections and extending longitudinally between and sealed to both fins.

19. A spray gun barrel construction including a barrel casting having two inwardly projecting longitudinal fins spaced circumferentially of the barrel, and a tube extending between and sealed to both fins, the fins cooperating with the tube and the bore of the barrel to afford two separate air passages of arcuate transversed section.

20. A spray gun barrel construction as per claim 19, including an arcuate web closing the rear end of one of the said separate air passages, the barrel being formed to provide an angular passage rearwardly spaced from the first of the said separate passages and connected to the second of the said separated passages, and the barrel having two inlet passages respectively leading to the said first passage and the said annular space.

21. The combination with a generally tubular spray gun barrel affording a central tube extending between two separated air passages and having a forward end portion through which both passages extend and within which the tubes terminates, the said end portion having a transverse bore intersecting one of the said passages and terminating forwardly of the tube, of a liner tube inserted in and sealed to the said bore and having a peripheral groove opposite the last named passages to afford an annular passageway connecting the parts of the last named passage which are respectively forward and rearward of the liner tube.
